UNITED STATES PATENT OFFICE.

SAMUEL RIVELIS, OF PHILADELPHIA, PENNSYLVANIA.

DESIGN FOR A SHOE ORNAMENT.

53,751.

Specification for Design.

Patented Aug. 26, 1919.

Application filed August 17, 1918. Serial No. 250,403. Term of patent 14 years.

To all whom it may concern:

Be it known that I, SAMUEL RIVELIS, a citizen of the United States, and a resident of Philadelphia, in the county of Philadelphia and State of Pennsylvania, have invented a new, original, and ornamental Design for Shoe Ornaments, of which the following is a specification, reference being had to the accompanying drawings, forming a part thereof.

Figure I is a perspective view of my shoe-ornament; and Fig. II, is a central vertical section showing the contour of my shoe ornament.

I claim:

The ornamental design for a shoe-ornament as shown.

SAMUEL RIVELIS.
